UNITED STATES PATENT OFFICE.

BERT R. BENJAMIN, OF OAK PARK, AND CHARLES PEARSON, OF CHICAGO, ILLINOIS,
ASSIGNORS TO INTERNATIONAL HARVESTER COMPANY, A CORPORATION OF NEW
JERSEY.

AUTOMATIC PITMAN.

Application filed December 23, 1918. Serial No. 268,086.

To all whom it may concern:

Be it known that we, BERT R. BENJAMIN and CHARLES PEARSON, citizens of the United States, and residents, respectively, of Oak

5 Park, in the county of Cook and State of Illinois, and of Chicago, in the county of Cook and State of Illinois, have invented certain new and useful Improvements in Automatic Pitmen, of which the following

10 is a full, clear, and exact specification.

Our invention relates to pitman connections, and more especially to pitman connections for mowers and like machines.

The object of our invention is to provide 15 means whereby the wear between the pitman and the associated and cooperating parts of the machine is automatically compensated for and the parts are at all times held in proper adjustment.

20 A further object is to provide means which may be easily and quickly manipulated to connect the pitman to the cooperating part and disconnect the pitman therefrom.

These objects are attained in the present 25 instance by the use in connection with resilient pitman straps of controlling means by which the straps may be clamped; further, by the use of means by which the straps may be spread apart to release the cooperating 30 bearing member, and still further by the use of a controlling member which has parts thereof adapted to clamp and has also parts adapted to spread the straps. Means may also be provided for retaining the strap 35 controlling member in its various positions of adjustment, such as in clamping position and in spreading position.

In working out the embodiment of our 40 invention illustrated, it has also been found advisable,—although it is not necessary,—to so form a portion of the controlling member that this portion will so engage the cooperating bearing member with which the pitman is connected, as to separate the pit- 45 man from the bearing member as the straps are spread.

In the accompanying drawing we have 50 illustrated one embodiment of our invention, and in this drawing,—

Figure 1 shows a top plan view of the grassward end of the pitman having our improved clamping device mounted thereon;

Fig. 2 is a side elevation of the construction shown in Fig. 1, the controlling member being shown in clamping position; 55

Fig. 3 is a view similar to Fig. 2, but with the controlling member shown in strap spreading position; and

Fig. 4 is a plan view of the device similar to Fig. 1 but with the controlling member 60 shown in position to spread the straps.

The pitman connection with which our improved strap controlling member is used has the usual resilient straps 11 and 12 secured in any suitable manner to the grass- 65

ward end 13 of the pitman, and these straps have formed on their grassward ends spherical bearing surfaces 14 which coact with the spherical bearing member 15 secured to the knife head of the mower or to any other 70 suitable element which it is desired to operate with the pitman. The strap controlling member is made in the form of a lever having a central portion 16 pivotally and reciprocally mounted in slots 17 formed in 75

the straps 11 and 12, these slots registering with each other. The controlling member is provided at the extremities of the central portion 16 with spaced fingers 18 having inclined bearing surfaces 19 formed on their 80

inner portions. These inclined bearing surfaces coact with inclined cam surfaces 20 formed on the straps 11 and 12, and the fingers 18 in their position of adjustment where the pitman straps are spread apart, 85

seat in depressed portions 21 formed in the pitman straps adjacent the cam surfaces 20, these depressions being provided to permit the spread of the pitman straps to release 90

the cooperating bearing member. The controlling member is provided at its end opposite that formed by the fingers 18 with a member 22 adapted to seat on the upper surfaces of the pitman straps when the controlling member is in clamping position, 95

and having inclined side edges 23 which engage the inner surface of the pitman straps as shown in Fig. 4, and spread these straps apart when the controlling member is in strap spreading position.

100 In order to lock the controlling member in spreading and also in clamping position, a toggle construction has been provided including a link member 24 having spaced

lugs 25 pivoted to a lug 26 which is formed on and projects from the central portion 16 of the controlling member. This member 24 has a rearwardly extending shank portion 25' and a spring 26' encircles the shank portion and bears at one end against a shoulder 27 formed on the member 24, and at its opposite end is seated in a socket 28 formed in the grassward end of the pitman.

10 By locating the pivot of the member 24 in offset relation with respect to the central portion 16 of the controlling member, the spring 26' fulfills a double function, namely, locking the controlling member in clamping position as shown in Fig. 2, and also locking the controlling member in spreading position as shown in Fig. 3. In this connection it will be noted that the central portion 16 is not only capable of rotary movement, but 15 is also capable of bodily movement longitudinally with respect to the straps 11 and 12 for automatically taking up wear on the bearing members.

Having described the construction of our 25 improved pitman strap controlling member, we will now set forth briefly the operation of the same.

In its clamping position the controlling member rests with its portion 22 seated on 30 the upper edges of the pitman straps and with the fingers 18 engaging the cam surfaces 20. In this position the spring 26' forces the fingers grasswardly or forwardly so that the inclined bearing surfaces 19 on 35 the fingers will slide on the cam surfaces 20 of the pitman to a position in which the spherical bearing portions of the straps are in proper engagement with the spherical bearing member with which they cooperate. 40 As wear occurs between these cooperating parts, the spring constantly forces the fingers still further forwardly, thereby taking up the wear. It will be noted that the rotary movement of the fingers 18 of the 45 pivoted portion 16 effect a relatively considerable adjustment of the straps 11 and 12, while the bodily movement of these fingers effects a relatively slight adjustment of the straps 11 and 12. In other words, by reason 50 of the cam surfaces 20 and 21 the rotation of the lever 22 from the position shown in Fig. 3 to the position shown in Fig. 2, effects a considerably greater clamping of the straps 11 and 12 than does the bodily movement of the locking lever 22.

By means of this construction also a great latitude is provided for the size of the bearing member with which the pitman is to cooperate, that is, if a large bearing member 60 is inserted between the pitman straps, the fingers 18 will be forced rearwardly thereby against the tension of the spring, whereas if a smaller member is to be used the spring automatically forces the fingers forwardly. The spring 26' also acting below

the pivot of the controlling member locks this controlling member in clamping position.

When the operator desires to release the straps from the cooperating member, the portion 22 of the controlling member is thrown in an anti-clockwise direction to the position shown in Fig. 3, where this member will engage with the spherical bearing member and in addition to spreading the pitman straps apart through the inclined edges 23 of the portion 22, will lift the pitman straps on the bearing member and force these members apart. When it is desired to again place the pitman and the cooperating member in operating position, pressure is exerted on the pitman straps thereby raising the member 22 until the bearing member 16 is disposed between the spherical bearing portions 14 of the straps, and the portion 22 of the controlling member is then swung in a clockwise direction, thereby clamping the straps in proper adjustment on the bearing member.

While we have in the above specification described one embodiment which our invention may assume, it should be distinctly understood that this embodiment is shown merely for the purpose of illustrating the invention, and that modifications may be made without departing from the spirit and scope of the invention as expressed in the following claims:

1. In a pitman having resilient straps, means including a member having reciprocable and rotary movement with respect to said pitman for forcing said straps toward each other.

2. In a pitman having resilient straps, means including a member having a reciprocable and rotary movement with respect to said pitman for forcing said straps toward each other, and resilient means for actuating said member to clamping position.

3. In a pitman having resilient straps, means including a member having a reciprocable and rotary movement with respect to said pitman for forcing said straps toward each other, and single means for locking said member in a plurality of positions of adjustment.

4. In a pitman having resilient straps, means including a member having a rotary movement with respect to said straps for forcing said straps toward each other and for spreading said straps, and resilient means for holding said member in clamping or spreading position.

5. In a pitman having resilient straps, means including a member having radial movement with respect to said straps for clamping and for spreading said straps, and single resilient means for holding said member in clamping or spreading position.

6. In a pitman having resilient straps,

means including a member having a rotary movement with respect to said straps for clamping and spreading said straps, and toggle locking means for locking said member in clamping or spreading position.

5 7. In a pitman having resilient straps, means including a member having spaced fingers slidably engaging said straps and mounted for rotary and reciprocable movement with respect thereto.

10 8. In a pitman having resilient straps, strap controlling means, spaced fingers adapted to force said straps toward each other, and a member for actuating said spaced fingers and also for spreading said straps.

15 9. In a pitman having resilient straps, a strap controlling member having a central portion rotatably and slidably mounted in 20 registering slots in said straps for forcing said straps to clamping position.

25 10. In a pitman having resilient straps, a strap controlling member having a central rotatable portion, spaced fingers carried by said central portion and adapted to clamp said straps, and a member also carried by said central portion for operating said controlling member.

30 11. In a pitman having clasping straps, a pivotally mounted member movable bodily with respect to said straps, and means for locking said movable member against pivotal movement, said means effecting a bodily movement of said member when 35 locked against pivotal movement.

35 12. In a pitman having clasping straps, a pivotally mounted member movable bodily with respect to said straps, and resilient means for locking said movable member 40 against pivotal movement, said means effecting a bodily movement of said member when locked against pivotal movement.

45 13. In a pitman having clasping straps, a pivotally mounted member movable bodily longitudinally with respect to said straps, and means for locking said movable member against pivotal movement, said means effecting a bodily movement of said member when locked against pivotal movement.

50 14. In a pitman having clasping straps, a member mounted for pivotal movement and carried by said straps and movable bodily relative thereto for adjusting said straps, the pivotal movement of said member effecting relatively considerable adjustment of said straps while said bodily movement of said member effects a relatively slight adjustment of said straps.

55 15. In a pitman connection, a bearing member, oppositely disposed clamps engaging said bearing member, a fork pivotally and longitudinally movable relative to said clamps for closing said clamps upon said

fork and movable therewith for forcing said clamps apart.

16. A pitman having resilient straps, means including a forked member having reciprocable and rotary movement with respect to said pitman for adjusting said straps, the rotary movement of said member effecting a relatively considerable adjustment of said straps while the reciprocable movement of said member effecting a relatively slight movement of said straps.

70 17. In a pitman having resilient straps, a fork member disposed between said straps and means for rotating and reciprocating said member relative to said straps.

75 18. In a pitman having resilient straps, said straps having aligned apertures therein and a member passing through said apertures slidably rotatably engaging said straps for controlling the adjustment of said straps.

80 19. In a pitman having resilient straps, said straps having aligned apertures therein and a rotary and reciprocable member passing through said apertures and slidably 85 engaging said straps for controlling the adjustment of said straps.

85 20. In a pitman having resilient straps, said straps having aligned apertures therein and a rotary and reciprocable member passing through said apertures and slidably 90 engaging the outside surfaces of said straps for controlling the adjustment of said straps.

95 21. In a pitman having resilient straps, a forked member disposed between said straps, a spring connected with and adapted to actuate said member and means for rotating and reciprocating said member relative to said straps.

100 22. In a pitman having resilient straps, said straps having aligned apertures therein and a single member passing through said apertures and tensionally connected to said pitman for controlling the adjustment 105 of said straps.

110 23. In a pitman having resilient straps, means including a member having a rotary movement with respect to said straps for clamping or spreading said straps, and single resilient means for holding said member in clamping or spreading position.

115 24. In a pitman having resilient straps, a clamping member slidably engaging both of said straps, a link pivotally connected 120 with said member and means for tensionally connecting said link with said pitman.

125 25. In a pitman having resilient straps, a forked member disposed between said straps and slidably engaging the outer surfaces of said straps, a link pivotally connected with said member and means for tensionally connecting said link with said pitman.

130 26. In a pitman having clasping straps, a

65 bearing member, and means carried by said

plurality of different camming surfaces formed on the outer sides of each of said straps, and a member mounted on said straps engageable with the camming surfaces of 5 both of said straps for clamping said straps.

27. In a pitman having clasping straps, said straps having double camming surfaces on the outer sides thereof, and a member mounted on said straps and engageable with 10 the double camming surfaces of both of said

straps for adjusting said straps relative to each other.

In testimony whereof we affix our signatures in the presence of two witnesses.
